UNITED STATES PATENT OFFICE

HARRY C. HOWER, OF CHICAGO, ILLINOIS

DESIGN FOR AN AUTOMOBILE TIRE

Application filed January 28, 1929. Serial No. 29,801. Term of patent 14 years.

To all whom it may concern:

Be it known that I, HARRY C. HOWER, a citizen of the United States, residing at Chicago, in the county of Cook and State of Illinois, have invented a new, original, and ornamental Design for Automobile Tires, of which the following is a specification, reference being had to the accompanying drawing, forming a part thereof.

In the drawing:

Figure 1 is a plan view of a portion of a tire embodying the present design;

Figure 2 is a fragmentary side elevational view of the tire shown in Figure 1; and

Figure 3 is a fragmentary transverse radial section, taken on the line 3—3 of Figure 1.

I claim:

The ornamental design for an automobile tire, as shown.

In witness whereof I hereunto subscribe my name this 24th day of January, 1929.

HARRY C. HOWER.
